BROOM SHOULDER

Donald G. Ray, Garland, Tex., assignor to All-American Manufacturing, Inc., Winnsboro, Tex.

Continuation of design applications Ser. No. 17,959 and Ser. No. 17,984, both June 30, 1969. This application Dec. 9, 1970, Ser. No. 26,372

Term of patent 14 years

Int. Cl. D4—01

U.S. Cl. D4—4

FIG. 3

FIG. 1

FIG. 4

This is a continuation of previously filed applications, Ser. Nos. 17,959 and 17,984, filed June 30, 1969, for Broom Shoulder.

FIG. 1 is an elevation view of any side of a broom shoulder showing my new design;

FIG. 2 is a top view thereof;

FIG. 3 is a top perspective view thereof; and

FIG. 4 is a bottom perspective view thereof.

I claim:

The ornamental design for a broom shoulder, substantially as shown and described.
